(57) CLAIM

The ornamental design for a basketball model as shown and described.

DESCRIPTION

FIG. 2 is a front view of the claimed design of FIG. 1;
FIG. 3 is a rear view of the claimed design of FIG. 1;
FIG. 4 is a left side view of the claimed design of FIG. 1;
FIG. 5 is a right side view of the claimed design of FIG. 1;
FIG. 6 is a top view of the claimed design of FIG. 1;
FIG. 7 is a bottom view of the claimed design of FIG. 1;
FIG. 8 is a front, top left perspective view of the claimed design for a basketball model, according to a second embodiment;

FIG. 9 is a front view of the claimed design of FIG. 8;
FIG. 10 is a rear view of the claimed design of FIG. 8;
FIG. 11 is a left side view of the claimed design of FIG. 8;
FIG. 12 is a right side view of the claimed design of FIG. 8;
FIG. 13 is a top view of the claimed design of FIG. 8; and,
FIG. 14 is a bottom view of the claimed design of FIG. 8.
The broken line showing is included for the purpose of illustrating portions of the “article” and forms no part of the claimed design. The stippled areas represent a contrast in color.

1 Claim, 14 Drawing Sheets
